SKIRT AND METHOD OF MAKING THE SAME

Irving A. Winter, Woodmere, N. Y.

Application January 5, 1938, Serial No. 183,404

2 Claims. (Cl. 2—211)

The present invention relates to wearing apparel and particularly to skirts, either separate or as parts of dresses, and comprises both a novel method of making skirts and the product made thereby. More specifically, the invention comprises a skirt made from a plurality of gores of novel shape sewed together in such a way as to give a straight line appearance throughout the length but with maximum fullness at the bottom without the effect of a flare.

For an understanding of the invention reference may be had to the accompanying drawing of which—

Fig. 1 is a front view of a dress having a skirt embodying the invention;

Fig. 2 is an enlarged view of one of the novel gores;

Fig. 3 is an enlarged detail view illustrating the method of joining the gores to form the skirt 20 of Fig. 1;

Fig. 4 is a fragmentary perspective view of a portion of the skirt illustrating the manner in which the gores cause the skirt to hang in folds; and

Fig. 5 is a view showing the lower portion of the skirt laterally extended.

The skirt 2 illustrated in the drawing is made of a plurality of gores 4 each preferably of the form illustrated on a larger scale in Fig. 2. As shown best in Fig. 2 each gore is cut to have an abrupt change in shape and width, which, in the particular embodiment of the invention illustrated, occurs at or near the knees of the wearer. This abrupt change in shape and width is indicated in the drawing as beginning at 6, 6, where the sides of the lower portion of the gore form convex curves 7 meeting the relatively vertical sides of the upper portion of the gore. Above the points 6 the gore gradually tapers on a small bias to the waist line 8. Below the points 6 and curves 7, the gore increases in width on a larger bias to three or more times that at the waist line.

In making the skirt the gores 4 are sewn together along their sides as shown in Fig. 3. In the completed skirt the curves 7 extend inwardly as shown best in Fig. 4 and the lower portion of the skirt hangs naturally without pressing in folds which have the appearance of definite pleats. As shown in Fig. 1, the skirt when worn does not flare or bulge at the bottom but retains the slim straight lines of the upper portion. The relatively great width of the skirt at the bottom combined with the natural hang 55 in folds due to the convex curves 7, gives com-

plete freedom of action to the wearer without sacrifice of slim appearance. The fullness of the skirt is best shown in Fig. 5 which illustrates the way the skirt opens out when the wearer whirls or spins about.

As heretofore indicated, it is the provision of the convex curves 7 forming the abrupt change in shape of the gore which permits the skirt to have fullness at the bottom without flaring; these curved portions in the completed skirt 5 forming, in effect, internal pockets from which hang the folds. Each curved portion of the gore may be considered as a plurality of different bias sections joining the short bias of the elongated upper portion of the gore with the longer bias of the lower or flared portion of the gore.

The invention has now been described with particular reference to the preferred embodiment thereof. Obviously various changes could be made without departing from the spirit of the 20 invention. For example, the relative widths and lengths of the top and bottom portions of the gores could be changed and the curvature at the junction of the bias sections could be varied. Although as illustrated, the complete skirt is 25 preferably fashioned from a plurality of identical gores, this is not essential as many of the advantages of the invention would be retained where part only of the skirt was so made, as for example, where fullness in the front or sides 30 only was desired.

The following is claimed:

1. A skirt having a relatively close fitting upper portion and a lower portion of greater fullness hanging in non-flaring folds from the upper 35 portion, the entire skirt being composed of a plurality of substantially identical gores each of the full length of the skirt and each cut to have an abrupt increase of width at the point corresponding to the top of the folds, the abrupt 40 change in width of each gore being in the form of convex curves the edges of which, when adjacent gores are sewn together in the completed skirt, extend inwardly toward the wearer.

2. A skirt having gores so cut as to make it 45 close-fitting for a portion of its length with substantial fullness at the bottom, each gore being of the full length of the skirt and cut to have an abrupt increase in width where the fullness of the skirt begins, the abrupt change in width being in the form of convex curves the edges of which, when adjacent gores are sewn together in the completed skirt, extend inwardly toward the wearer.
